RESTAURANT BUILDING

Kenneth L. Swarthout, Brunswick, Ga.
(21010 St. Francis St., Farmington, Mich. 48024)

Filed Nov. 30, 1970, Ser. No. 24,605

Term of patent 14 years

Int. Cl. D25—03

U.S. Cl. D13—1

FIG. 3

FIG. 4

FIG. 1 is an elevational view of a restaurant building embodying my invention;

FIG. 2 is a top plan view of FIG. 1;

FIG. 3 is a vertical transverse sectional view taken along lines 3—3 in FIG. 2, and

FIG. 4 is a sectional plan view taken along line 4—4 in FIG. 1.

I claim:

The ornamental design for a restaurant building, as shown.
